UNITED STATES PATENT OFFICE.

JOHN E. LESTER, OF OMAHA, NEBRASKA.

MACHINE FOR SEALING AND STAMPING ENVELOPS.

SPECIFICATION forming part of Letters Patent No. 746,114, dated December 8, 1903.

Application filed June 14, 1902. Serial No. 111,705. (No model.)

To all whom it may concern:

Be it known that I, JOHN E. LESTER, a citizen of the United States, residing at Omaha, in the county of Douglas, State of Nebraska, have invented certain new and useful Improvements in Machines for Sealing and Stamping Envelops, of which the following is a specification.

My invention relates to envelop sealing and stamping machines; and the object thereof is to provide a mechanism capable of using stamps from the sheets in which they are sold and which will not require hand-feeding of the envelops which are to be sealed and stamped.

My invention lies in the improved envelop and stamp feed, in the moistening and sealing devices, and in certain other new and useful combinations and arrangements of parts, as will be more fully described hereinafter.

A mechanism embodying my invention is shown in the accompanying drawings, in which—

Figure 1 is a front elevation of the machine. Fig. 2 is a right-hand end elevation of the same. Fig. 3 is a sectional view taken on the line *x* *x* of Fig. 1. Fig. 4 is a sectional plan view taken on the line *y* *y* of Fig. 2. Figs. 5 and 6 are details showing the action of the stamp-feed and reverse movements. Fig. 7 is a detail end view of the stamp-carriage, feed-pinion, and the spring-clutch therein. Fig. 8 is a sectional detail of the same. Fig. 9 is a detail end elevation of the stamp-die-actuating arms. Fig. 10 is a detail showing the ejector-release lever. Fig. 11 is a plan view illustrating the operations of tripping and resetting the ejector.

In the construction shown suitable frames 1 and 2 are joined together and held in their proper relative positions by the bars 4 and 5. Ribs 27, extending from the inner faces of the frames 1 and 2, support a top or table 26.

At the rear side of the table 26 and secured to the bar 4 is an envelop receptacle or magazine 74, which is open at one end, so that the envelops may be readily inserted therein, and has an adjustable side 92, which may be moved back and forth to accommodate different sizes of envelops. A follower 75 is arranged within the envelop-magazine and is normally pushed upward by the conical coiled

springs 90. The envelops A are placed face downward upon this follower, as shown in Fig. 3. Tongues 91 on the follower pass through corresponding vertical slots in the movable side 92 and support the rear portions of the envelops when the larger sizes of the same are used. Other tongues 109 on the movable side 92 project over the top of the envelop-magazine and form a stop which engages the rear portions of the envelops and holds the same down in the magazine against the upward pressure of the follower. The flap upon the uppermost envelop is therefore free to rise, as shown in Fig. 3.

An envelop-carrier and flap-moistener 21, comprising a flaring inclined hollow foot 21^a and a tubular shank 14, is suspended above the magazine by a horizontal support consisting of a rod 10. The rear end of rod 10 is supported and finds a bearing in the standard 83, resting on the base-plate 94, and the forward end of the rod is supported by a bearing 11^a on an arm 11, extended from the side frame 1. At the central part of the said rod is a yoke through which passes the stem or shank 14 of the carrier and moistener 21. The stem 14 has collars 13 thereon above and below the rod, and centering-springs 15 are placed between the collars and the rod, which springs permit the carrier to be raised or lowered for the purposes hereinafter set forth, but return the carrier to its normal central position when released. One side of the bearing 11^a is open, and the part of the rod 10 which extends through the bearing is rectangular in section. The rod therefore cannot turn in its bearings. A pin 12 in the bearing 11^a extends into a slot in the rod and prevents the same from being drawn out of the open-sided bearing. A connecting-rod 9 is connected by a pin to the square portion of the horizontal rod and extends to a pin upon a crank-wheel 8 on a suitably-driven shaft 7. The driving-shaft 7 is journaled in a bearing 6 upon a standard 6^a and also in the side frame 2 and in a bracket 3, secured to said frame. When the shaft 7 is turned and the wheel 8 rotated, motion is communicated through the connecting-rod 9 to the horizontal rod 10 and reciprocates the same, thereby moving the envelop carrier and moistener to and fro transversely of the magazine. A guide-bar 18 is supported

100

alongside the carrier-shank 14 by suitable connecting-pieces 17 and 19, extending, respectively, to the bearing 11 and standard 83. During the forward stroke of the carrier a pin 20 on the side of the shank 14 engages a cam-surface 18^a at the rear end of the bar 18 and then travels along the underside of the guide, which thus holds the carrier down close to the table 26. At the end of the forward stroke 10 of the carrier the latter is raised by the tension of the lower spring 15 and the pin 20 rises above the point of an inclined face 18^b at the forward end of the guide 18. On the rearward stroke of the carrier the pin runs 15 above the guide, being raised by the inclined surface 18^c. On reaching the end of the rearward stroke of the carrier the pin 20 drops off the rear end of the guide and on beginning the next forward stroke is again engaged by the inclined surface at the rear end of the guide and carried under the same during the forward stroke. The carrier and moistener is thus depressed from its normal position during its forward stroke and raised 25 above said position during its rearward stroke.

The envelops are placed in the receptacle or magazine with the flaps up and at the front side of the magazine. The fingers 109 composing the stop are made short enough not 30 to cover the flaps, so that the flap of the uppermost envelop projects above the top of the box, and when the carrier is depressed by the guide and carried forward the point of the carrier engages with the flap of the 35 uppermost envelop and pulls the said envelop out of the receptacle and onto the table 26. When the carrier is raised at the end of the forward stroke, the envelop is left lying on the table 26. The carrier and the shank 40 thereof are hollow and are filled with water, and the lower end of the carrier is filled with sponge or other porous substance to permit a limited amount of the water to pass through and onto the upper side of the envelop under 45 the flap.

Immediately above the forward edge of the table 26 is a shaft 24, which is journaled in the side frames 1 and 2. On this shaft is secured the sealing-press 23. The under side 50 of the sealing-press is padded with felt, soft rubber, or other elastic substance 25. An arm 22 extends upward from the sealing-press and is joined by the connecting-rod 16 to the horizontal rod 10, so that when the 55 said rod 10 moves forward the said arm is pushed forward and the sealing-press is raised to an approximately vertical position, and when the rod 10 is at the end of its rearward stroke the padded face 25 of the said press is 60 pressed firmly onto the table 26. Beneath the table are a pair of shafts 29 and 30, which are journaled in the side frames 1 and 2 and which serve as supports and guides for the end frames 28 of a stamp-carriage B. The 65 frames 28 are held together by a rear bar 31 and a ratchet-bar 33. Feed-rolls 87, 88, 88, and 89 and pressure-rolls 70 70 70 70 are

journaled in the end frames 28 of the carriage and move back and forth therewith. The pressure-rolls 70 are preferably covered 70 with rubber or other elastic material, and the feed-rolls are geared together by pinions 71 71 71, intermediates 72 72 and 73, so that all the feed-rolls revolve together and in the same direction. 75

A strap 65 is secured to the frame 28 and passes over a small idle pulley 66 on the side frame 1 and downward to the wheel 67. This wheel is arranged to rotate on a fixed shaft 69, which is secured to lugs on the side frame 80 1. A spring 68 is secured at one end to the shaft 69 and at the other to the wheel 67, so as to exert a tension on the wheel and tend to wrap the strap around the same and to draw the stamp-carriage toward the left side 85 of the machine.

As postage-stamps are usually sold in sheets of one hundred stamps, which are arranged in ten rows of ten stamps each, I prefer to so construct the mechanism as to accommodate 90 such sheets, although the mechanism illustrated might be arranged for use with sheets of any size.

Between the intermediate feed-rolls 88 88 of the stamp-carriage and resting on the bar 95 5 is a rectangular guide-box 76, the upper edge of which is flush with the tops of the feed-rolls. In this box is arranged a stamp-punch 85, the top edge of which normally rests even with the top edge of the box 76. 100 On the stem of the punch are a pair of small collars, between which extend the ends of a small forked arm 86, attached to the shaft 62. The shaft 62 is journaled in the side frames 1 and 2, and passing through the frame 105 1 has a small lever-arm 63 thereon. On the same end of the shaft 24 is a crank or arm 64, as shown in Figs. 1 and 9, which when the sealing-plate is pressed down, as before described, strikes the arm 63, presses the same 110 downward, raises the forked arm 86, Fig. 3, and raises the punch 85 up through the opening 93 in the table 26.

The shaft 30 has a keyway 30^a therein which is engaged by a feather in the feed-roll 89, so 115 that the turning of the said shaft turns the said roll, while the roll is also permitted to slide along the shaft. The sheet of stamps, as before mentioned, is placed between the feed and pressure rolls by inserting the edge 120 of the sheet between the front roll 87 and the first pressure-roll 70 with the gummed side up and then turning the knob 60 on the end of the shaft 30 until the first stamp at the left end of the sheet appears under the opening 93 in the table 26, the carriage being in the right-hand position. (Shown in Fig. 1.) The front part of the sheet of stamps is prevented from dropping down between the rolls by the guide-plates 32^a and 32. 125

It will be seen that when a stamp is in position under the opening 93 if the stamp-punch be raised the stamp will be cut off and carried up through the opening by the punch. 130

Now as the envelops are carried across the table by the carrier, as before described, they pass over a sponge 84^a, placed in a small depression or cup 84 in the top of the table, which sponge is kept wet by water conducted thereto by a small pipe 80 from the tank 81, as shown. As the envelop is moistened on the under side and as it is held down firmly by the sealing-press, when a stamp is carried up and pressed against it by the punch it will stick to the envelop.

Arrangements are made for feeding the stamps into position above the punch as follows: On the shaft 7, between the side frame 2 and bracket 3, is a pinion 50, which meshes with a gear 48 on shaft 49, which is also journaled in frame 2 and bracket 3. On this shaft 49 is a pinion 47, which meshes with an operating-gear 42 on a shaft 51. The said gears and pinions are so proportioned that the gear 42 will make one revolution to each twenty revolutions of the shaft 7. The gear 42 is divided into twenty equal divisions, and at nine of these consecutive divisions a series of pins 46 are placed on one side of the said gear. At the opposite nine consecutive divisions are placed a series of pins 45 on the other side of the gear, the divisions between each series being left without pins, as shown in Figs. 5 and 6. Adjacent to the lower part of the gear and arranged to engage with the pins 46 and 45, respectively, are the star-wheels 54 and 55, which are secured to gears 53 and 52, respectively, Figs. 1, 5, and 6. As the pins 45 and 46 pass the star-wheels the same are turned forward one division for each pin. The gear 52 meshes with a pinion 56, secured to the shaft 30 by a spring-clutch, as herein-after described, so that each time one of the pins 45 passes the star-wheel 55 the feed-rolls of the stamp-carriage are moved a distance equal to the length of one stamp. Thus when the first stamp is placed under the opening 93 in the table and the same is cut off and affixed to the envelop the sheet is fed transversely of the machine and a second stamp is moved forward under the opening by the time another envelop is in position to be stamped, and so on until the first row of stamps is used. Now for the first row of stamps the carriage is in the position shown in Fig. 1 and is held in this position against the tension of the spring 68 by a pawl 34, engaging with one of the teeth on the rack 33. The pawl 34 passes through the bar 5 and is held in position by a forked lever 36, which is pivoted on the under side of the bar 5 and at its other end holds a similar pawl 35, adapted to move upward when the first pawl is moved down, and vice versa, the pawls and connecting-lever forming a dog for effecting the step-by-step release of the carriage. Attached to the lever 36 is an arm 37, which is pivotally connected with a longitudinally-movable rod 38, which rod is pivoted to the end of a tripping-lever 39. The lever 39 is pivoted on a pin 40 on the frame 2 and has a

forked upper end 41, extending on each side of the gear 42. Diametrically opposite each other and on opposite sides of the operating-
70 gear 42 are wedge-shaped projections 43, which as they pass the ends 41 of the forked lever push the same in and out alternately, thereby pushing back and forth the rod 38 and alternately raising and depressing the
75 pawls 34 and 35. As the pawl 34 is depressed and the pawl 35 raised the carriage is pulled over by the spring until the first tooth of the rack engages with the pawl 35, when the movement of the carriage is stopped until the
80 forked lever 39 is moved by the succeeding projection 43 in the opposite direction, when the positions of the pawls will be reversed, the first pawl catching the second tooth of the rack 33, and so on. The carriage thus moves
85 forward half the distance from one of the teeth of the rack to another each time the forked lever is pushed by one of the projections 43 on the gear 42. Now as the distance between the ratchet-teeth is twice the width
90 of one row of stamps and the distance between the similar faces of the pawls 34 and 35 is the same as the width of one row of stamps it will be seen that each time the carriage is shifted a fresh row of stamps is presented to be cut off and affixed to the envelops; but it is also necessary as each row of stamps is finished and a new row started that the direction of feed in the carriage be reversed in order to cut off the stamps in the
100 next row successively, and this is provided for as follows: Meshing with the pinion 56, Figs. 1, 5, and 6, is an intermediate pinion 57, which also meshes with the gear 53, carrying the star-wheel 54, which is intermittently
105 moved by the pins 46. Now as the direction of movement of the gear 53 is reversed by the intermediate pinion 57, when the carriage is moved by the gear 53 it will be in a direction opposite to that which it will be moved by the
110 gear 52. After the operating-gear 42 has made a half-revolution and one row of stamps has been cut off the opposing set of pins 46 on said gear operate the star-wheel 54 upon the gear 53, and the feed-rolls then turn intermittently
115 in the opposite direction, as will be evident. To prevent the setting of the star-wheels relatively to the gear 42 from being changed when placing a new sheet of stamps in the carriage, the pinion 56 is secured to the shaft
120 30 by the device shown in Figs. 7 and 8. A collar 102 is secured to the shaft 30 by a key 108, and on this collar is placed a circular spring 101, which is secured to the collar at one end by a pin 107 and bears against the
125 inside surface of the pinion 56 with sufficient tension to hold the same securely to the said shaft. The other end of the said spring 101 is secured by a pin 104 to a lever 103, which is pivoted by a pin 105 to the collar 102. The free end of the lever 103 is near the shaft 30, and by turning the sleeve 58 by means of the knob 59 thereon the said end of the lever 103
130 may be pushed out, thereby drawing inward

the free end of the spring and leaving the shaft 30 free to turn without moving the pinion 56 or changing the setting of the star-wheels.

5 The sealed and stamped envelops are thrown off the table by the ejector mechanism shown in Figs. 2, 4, and 10 and 11. A bell-crank lever 77 is pivoted on the table 26 at the rear central part thereof, and a spring 10 78 is secured to one end of the same, as shown in Figs. 4 and 11. A latch 79, carried by a lever 95, which is pivoted at 98 to the end of the envelop - magazine, normally holds the lever in the position shown against the tension of the spring 78. When the carrier 21 begins its forward stroke and the sealing-press 23 is in about the position shown in Fig. 3, a lug 99 on the side of the carrier strikes an inclined projection 96 on the upper side of 20 the lever 95, depresses the same, and releases the lever 77, which, being actuated by the spring 78, strikes the envelop and throws it off the edge of the table. As the carrier 21 continues on its forward movement the lug 25 99 engages with the lever 77, as indicated in dotted lines, Fig. 11, and pushes the same back to its original position, where it is caught and held by the latch 79 until the lever 95 is again depressed by the lug 99. As the carrier is raised up by the cam 18 on its backward stroke, it does not strike the projection 96 on said backward stroke, but passes over the same.

Having described my invention, what I 35 claim as new, and desire to secure by Letters Patent, is—

1. In an envelop-sealing machine, the combination with an envelop-magazine of a moistener arranged to moisten the envelops beneath their flaps, an intermittently-operated sealing-press and means for operating said moistener and sealing-press alternately.

2. In an envelop-sealing machine, the combination with an envelop-magazine having a 45 follower therein, of a moistener arranged to moisten the envelops beneath their flaps, an intermittently - operated sealing - press and means for operating said moistener and sealing-press alternately.

3. In an envelop-sealing machine, the combination with an envelop-magazine, of an intermittently-operated sealing-press, a reciprocating moistener arranged to moisten the envelops beneath their flaps and means for 55 operating said moistener and sealing-press alternately.

4. In an envelop-sealing machine, the combination with an envelop-magazine of an intermittently-operated sealing-press, a reciprocating moistener arranged to moisten the envelops beneath their flaps, means for operating said moistener and sealing-press alternately, and means for automatically ejecting the envelops from the press.

5. In an envelop-sealing machine, the combination with an envelop-magazine and an intermittently-operated sealing-press, of a re-

ciprocating moistener arranged to engage the envelops beneath their flaps and deliver them to the sealing-press, and means for operating 70 said moistener and sealing-press alternately.

6. In an envelop-sealing machine, the combination with an envelop-magazine having a stop at its outer end and a follower within the magazine adapted to force the envelops 75 against the stop, of an intermittently-operated sealing-press, a moistener arranged to engage the envelops beneath their flaps and deliver them to the sealing-press, and means for operating said moistener and sealing-press 80 alternately.

7. In an envelop-sealing machine, the combination with an envelop-magazine having a stop at its outer end and a follower within the magazine adapted to force the envelops 85 against the stop, of an intermittently-operated sealing-press, a moistener arranged to engage the envelops beneath their flaps and deliver them to the sealing-press, means for operating 90 said moistener and sealing-press alternately, and means for automatically ejecting the envelops from the press.

8. In an envelop-stamping machine, the combination with an envelop - magazine, a press, and means for automatically feeding 95 envelops from said magazine to said press, of means for automatically moistening the faces of the envelops, means for automatically feeding a stamp-sheet, and means for automatically cutting stamps from said sheet and applying them to the envelops while the latter are in the press.

9. In an envelop sealing and stamping machine, the combination with an envelop-magazine, a press, and means for moistening the 105 envelops beneath their flaps and for transferring them from the magazine to said press, of means for applying moisture to the faces of the envelops, means for automatically feeding a stamp-sheet and means for automatically cutting off stamps from said sheet and applying them to the envelops while the latter are in the press.

10. In an envelop sealing and stamping machine, the combination with an envelop-magazine, a sealing - press and a moistener arranged to engage the envelops beneath their flaps and carry them from the magazine to the sealing-press, of means for moistening the faces of the envelops and means for automatically applying stamps to the envelops while in the press.

11. In an envelop-sealing machine, the combination with an envelop-magazine having a stop at its outer end and a follower within 125 the magazine adapted to force the envelops against the stop, of an intermittently-operated sealing-press, a reciprocating moistener arranged to engage the envelops beneath their flaps and deliver them to the sealing-press, 130 means for operating said moistener and sealing-press alternately, and means for automatically ejecting the envelops from the press.

12. In an envelop sealing and stamping ma-

chine the combination with an envelop-magazine having a stop at its outer end and a follower within the magazine adapted to force the envelopes against the stop, of a sealing-
5 press, a reciprocating moistener arranged to engage the envelopes beneath their flaps and deliver them to the sealing-press, a stationary moistening device arranged in the path of the envelopes and adapted to moisten the faces
10 thereof, means for operating said reciprocating moistener and sealing-press alternately, and means for automatically applying the stamps to the envelopes while in the press.

13. In an envelop sealing and stamping ma-
15 chine the combination with an envelop-magazine having a stop at its outer end and a follower within the magazine adapted to force the envelopes against the stop, of a sealing-
20 press, a reciprocating moistener arranged to engage the envelopes beneath their flaps and deliver them to the sealing-press, a stationary moistening device arranged in the path of the envelopes and adapted to moisten the faces thereof, means for operating said recip-
25 rocating moistener and sealing-press succes-
sively, means for automatically applying the stamps to the envelopes while in the press and means for automatically ejecting the envelopes from the press.

30 14. In an envelop sealing and stamping ma-
chine the combination with an envelop-magazine having a stop at its outer end and a follower within the magazine adapted to force the envelopes against the stop, of a sealing-
35 press, a reciprocating moistener arranged to engage the envelopes beneath their flaps and deliver them to the sealing-press, a stationary moistening device arranged in the path of the envelopes and adapted to moisten the faces thereof, means for operating said recip-
40 rocating moistener and sealing-press succes-
sively, a punch for cutting off stamps from a stamp-sheet and applying them to the envelopes while in the press, and means for feeding
45 the stamps in sheet form to the punch successively.

15. In an envelop-sealing machine, a maga-
zine for the envelopes having an adjustable back with vertical slots therein, and a fol-
50 lower within the magazine having tongues ex-
tending through said slots.

16. In an envelop-sealing machine, the com-
bination with an envelop-magazine, of a seal-
55 ing-press, a moistener-support movable trans-
versely of the magazine, and a hollow moistener having a tubular shank connected to said support and having a hollow flaring foot adapted to engage the envelopes beneath their flaps and transport them from the magazine
60 to the sealing-press.

17. In an envelop-sealing machine, the com-
bination with an envelop-magazine having a stop at its outer end and a follower within the magazine adapted to force the envelopes
65 against the stop, of a sealing-press, a reciprocating moistener arranged to engage the envelopes beneath their flaps and deliver them

to the sealing-press, means for depressing the moistener during its forward movement and for elevating the moistener during its return movement, and means for operating said moistener and sealing-press successively. 70

18. In an envelop-sealing machine, the com-
bination with an envelop-magazine and a seal-
ing-press of a moistener-support movable
75 transversely of the magazine, a moistener car-
ried by said support and movable vertically
relatively thereto, said moistener being adapt-
ed to transport the envelopes from the maga-
zine to the press, and a guide arranged to de-
press the moistener during its forward move-
ment and to elevate the moistener during its
rearward movement. 80

19. In an envelop-sealing machine, the com-
bination with an envelop-magazine and seal-
ing-press, of a moistener-support movable
85 transversely of the magazine, a moistener car-
ried by said support and movable vertically
relatively thereto, said moistener being adapt-
ed to transport the envelopes from the maga-
zine to the press, a guide arranged to depress
90 the moistener during its forward movement
and to elevate the moistener during its rear-
ward movement, said guide consisting of a
bar extending parallel with the moistener-
95 support and having beveled ends arranged to
engage a projection upon the moistener.

20. In an envelop-sealing machine the com-
bination with a sealing-press and a magazine
100 of a moistener-support movable transversely
of the magazine, a moistener having a shank
extending through an opening in said sup-
port, said shank having collars thereon at
either side of the support and springs inter-
105 posed between the collars and support, and
a guide-bar arranged parallel with the sup-
port and having inclined ends adapted to en-
gage a part upon the moistener.

21. In an envelop-sealing machine, the com-
bination with an envelop-magazine, a sealing-
110 press and a reciprocating moistener arranged
to convey the envelopes from the magazine to
the press, of means for depressing the moistener
during its forward movement and for
raising said moistener during its rearward
115 movement, a spring-pressed ejector, a latch
for holding said ejector in its set position
and means connected with said moistener
for releasing the latch and for resetting the
ejector during the forward movement of the
120 moistener.

22. In an envelop-sealing machine, the com-
bination with an envelop-magazine, a sealing-
125 press, a reciprocating moistener arranged to
convey the envelopes from the magazine to the
press, of an ejector, a spring arranged to move
said ejector, means for holding said ejector
in its set position and means for automatic-
ally releasing and resetting the ejector.

23. In an envelop-sealing machine, the com-
bination with an envelop-magazine, a sealing-
130 press and a reciprocating moistener arranged
to convey the envelopes from the magazine to
the press, of an ejector comprising a pivoted

lever, a latch for holding said lever in its set position, a spring for moving said lever to eject the envelopes from the press and means operated by the moistener for releasing the 5 latch and for resetting the lever.

24. In an envelop-sealing machine, the combination with an envelop-magazine and a sealing-press of a moistener arranged to transport the envelopes from the magazine to the press, 10 a reciprocating support for said moistener, a link connecting said support with the press, a driving-shaft and a connecting-rod operated by said shaft and connected to the moistener-support.

15 25. In an envelop-stamping machine, the combination with a punch and means for reciprocating said punch, of a carriage having feed-rolls adapted to receive a sheet of stamps, means for intermittently operating said rolls 20 to bring the successive stamps in a row opposite the punch, means for automatically shifting the carriage after the last stamp in each row is cut off to bring another row of stamps in line with the punch, and means for 25 reversing the direction of movement of the feed-rolls when the carriage is shifted.

26. In an envelop-stamping machine, the combination with a punch for cutting off stamps from a stamp-sheet and applying them 30 to the envelopes, of a carriage and means for feeding a sheet of stamps alternately back and forth with an intermittent movement, and means for shifting the carriage at each reversal of the feed mechanism.

35 27. In an envelop-stamping machine, the combination with a stamp-affixing device and means for operating the same, of a carriage movable relatively to said device and having feed-rolls adapted to feed the stamps to said 40 affixing device, and means for intermittently operating said feed-rolls comprising an operating-gear having series of projections thereon, a star-wheel within the path of said projections, and gearing connecting said star-wheel operatively with the feed-rolls.

45 28. In an envelop-stamping machine, the combination with a punch and means for reciprocating said punch, of a carriage having feed-rolls adapted to feed the stamps in sheet 50 form to said punch and means for intermittently operating said rolls comprising a driving-shaft for the rolls, a pinion on said shaft, an operating-gear having a series of projections thereon, a star-wheel within the path of 55 said projections and a gear rotatable with the star-wheel and meshing with said pinion.

29. In an envelop-stamping machine, the combination with a punch and means for reciprocating said punch, of a carriage having 60 feed-rolls adapted to feed the stamps in sheet form to said punch and means for intermittently operating said rolls and reversing the same, comprising a driving-shaft for the rolls,

an operating-gear having two series of projections thereon, each series being on a different part of the operating-gear, a star-wheel arranged within the path of each series of projections and gearing connecting each of said star-wheels operatively with said driving-shaft. 65

30. In a machine for stamping envelopes, the combination with a stamp-affixing device of a carriage having feed-rolls adapted to feed stamps in sheet form to said device, means for operating said rolls intermittently to feed 70 each row of stamps to the affixing device, means for reversing the direction of the feed-rolls at the completion of each row and means for automatically shifting the carriage to bring the succeeding row of stamps in line 75 with the affixing device, comprising devices for releasing and stopping the carriage, an operating-gear and a tripping-lever connected to said device and adapted to be moved intermittently by said operating-gear. 80

31. In a machine for stamping envelopes the combination with a punch, of a carriage having feed-rolls adapted to feed the stamps in sheet form to the punch, means for operating said rolls intermittently to feed each row of 90 stamps to the punch, means for reversing the direction of the feed-rolls at the completion of each row and means for automatically shifting the carriage to bring a succeeding row of stamps opposite the punch comprising 95 an operating-gear having cam projections on its opposite sides, a lever having forked ends adapted to be engaged alternately by said projections, a dog operatively connected with said lever and a rack upon the carriage co-operating with said dog. 100

32. In an envelop sealing and stamping machine the combination with a punch, a pivotally-mounted sealing-press, and means for rocking said press, of means for operating 105 the punch each time the press is closed, comprising a shaft having an arm in engagement with the punch and a tappet-arm adapted to be engaged by an arm connected with the press. 110

33. In a machine for applying stamps to envelopes the combination with a carriage having feed-rolls, a driving-shaft for said rolls, a pinion, a clutch securing said pinion to said shaft, and gearing engaging said pinion for turning the same, of a hand device for turning the driving-shaft and means for releasing the clutch when the shaft is turned by the hand device. 115

In testimony whereof I affix my signature 120 in presence of two witnesses,

JOHN E. LESTER.

Witnesses:

JOHN HOOYT,
N. E. JONES.
